Term of patent 14 years

(Cl. D15—1)

Fig. 1.

Fig. 2.

Fig. 3.

Fig. 4.

Fig. 1 is a front perspective view of an occasional chair embodying our new design;

Fig. 2 is a view similar to Fig. 1, but with the back cushion removed and a portion of the seat cushion broken away to illustrate the back frame;

Fig. 3 is a rear perspective view of the chair with the cushions omitted; and

Fig. 4 is a rear perspective view of the chair as shown in Fig. 1.

The dominant features of the design reside in the portions shown in full lines.

We claim:

The ornamental design for an occasional chair, as shown and described.
